(57) **CLAIM**

The ornamental design for a knife cradle, as shown and described.

DESCRIPTION

FIG. 1 is a perspective view of a knife cradle showing my new design;

FIG. 2 is a top plan view thereof;

FIG. 3 is a left side elevational view thereof, the right side being identical thereto but a reverse image thereof;

FIG. 4 is a rear view thereof;

FIG. 5 is a front view thereof;

FIG. 6 is a bottom plan view thereof;

FIG. 7 is a top plan view identical to FIG. 2 but showing, in dotted-line form, a logo inscribed on the front face of the knife cradle; and,

FIG. 8 is a front view identical to FIG. 5 but showing, in dotted-line form, a logo inscribed on the front face of the knife cradle.
